UNITED STATES PATENT OFFICE.

HERMAN A. WAHLBORG, OF ELLIS, KANSAS.

HEN'S NEST.

Application filed October 12, 1922. Serial No. 594,060.

To all whom it may concern:

Be it known that I, HERMAN A. WAHLBORG, citizen of the United States, residing at Ellis, in the county of Ellis and State of Kansas, have invented certain new and useful Improvements in Hens' Nests, of which the following is a specification.

The present invention relates to an improvement in nests for laying hens and the object of the invention is to provide a nest with a plurality of compartments, one for each hen and having a common receptacle for the eggs in which they collect immediately they have been laid in each compartment.

Another object of the invention is to construct a hen's nest in the form of a cabinet with suitable ventilation and individual doors for each compartment making it possible to close some of the compartments, while others are left open.

Still another object of the invention is to attach said common receptacle to the cabinet in such a manner that it can easily be inspected without disturbing any of the hens and that this receptacle may be emptied irrespective of the open or closed compartments of the cabinet.

In the accompanying drawings one embodiment of the invention is illustrated, and

Fig. 1 shows a perspective view of a hen's nest;

Fig. 2 a vertical longitudinal section thereof;

Fig. 3 a section along line 3—3 of Fig. 2, and

Fig. 4 a perspective view of some of the details.

In the drawings reference numeral 10 represents the side walls of a hen's nest, which is built in the shape of a cabinet; reference numeral 11 is the rear wall and numeral 12 the front wall thereof. These walls are united in the usual manner as by riveting or soldering at the four corners. The top edges of the walls are on one level and have a flanged band 13 running along the four sides thereof. This flanged band has a Z-shaped cross section with an upright flange set inward as regards the side, front and rear walls of the cabinet and providing a seat as at 14 for the roof 15, which is removable, so that the inside of the cabinet can easily be inspected and cleaned.

The roof 15 has a triangular shaped eave 16 at each end and longitudinal runners 17

at the front and rear rigidly secured as by riveting or soldering. These eaves and runners are connected with the forwardly inclined roof portion 18 and the rearwardly inclined second roof portion 19. The second roof portion is wider than the forward roof portion and projects a considerable distance over the same as at 20 to provide a drip edge. This projecting part of the rear roof portion 19 is supported by means of an upstanding wall 21 rising from the forward roof portion 18 being rigidly connected to the projecting portion 20 as at 22. At intervals there are formed small windows 23 in the upright 21 by slitting the latter and bending the lip 24 formed in this manner and securing the latter to the underside of the rear roof portion 19 as at 25. In this manner the necessary ventilation for the hen's nest is provided. At 26 are shown a pair of handles for lifting the roof off the cabinet. The runners 17 and the eaves 16 are spaced sufficiently apart to fit closely over the upright inside flange 13 at the top of the cabinet in this manner holding the roof from slipping off the latter.

The cabinet is firmly secured to a base 27, which is preferably formed out of angle iron running along the back and side walls thereof. This base 27, however, terminates near the corners of the front wall 12 and does not reach across the same, so that when the cabinet is placed on the ground or floor, the bottom edge 28 of the front wall will be slightly raised above the floor or ground in order to permit the entering of air under this edge.

The middle portion of the front wall 12 is cut away as at 29 for the purpose of accommodating the receptacle for the eggs. This receptacle consists of a drawer 30 having a handle 31 in the middle thereof. A slanting bottom 32, which is higher at the rear end of the drawer, consists preferably of a sheet metal plate bent upwardly in the rear to form a rear wall 33 and in front to form a front wall 34, which is accordingly higher than the rear wall 33, the top edges of both being at the same level. This bottom plate is preferably flanged at the sides as at 35 in Fig. 2 and united to the plate sides 36 to complete the tray or drawer 30. A pair of angles 37 secured to the rear wall 11 and base 27 form guides for the drawer 30 and extend some distance forwardly beyond the front wall 12 of the cabinet in or-

der to accommodate the drawer 30, which is longer than the distance between the front and rear walls of the cabinet as best seen in Figs. 1 and 3. The interior, that is to say, the bottom and sides as well as front and rear portions of the drawer 30 are all lined by some suitable padding 38 to prevent the breaking of the eggs, when they collect in the drawer, the latter being longer, as already described, than the cabinet. A lid 39 hinged as at 40 on the front wall 12 is furnished to close the projecting part of the drawer 30. This lid 39 is preferably made of sheet metal with depending flanges 41 covering partly the sides of the drawer and has a transparent center portion 42 of glass or mica, so that the front end of the drawer may be inspected without lifting the lid or pulling out the drawer.

In the drawings the cabinet is shown with three compartments, but it is evident, that any number of such compartments may be provided according to the requirements and number of hens, for which it is intended to be used. These compartments are formed by internal partitions 43 running between the front and rear walls of the cabinet and extending up under the roof as at 44 so as to completely divide the compartments from each other. These partitions 43 are preferably made of mesh fabric in order to facilitate the circulation of air through the cabinet. Each of these compartments has a separate bottom 45 preferably made of sheet metal and firmly united to the walls of the cabinet as at 46 as well as to the partitions as at 47. Each bottom is made in the shape of an inverted pyramidal frustum, in the center of which is provided an aperture 48 of a size large enough to permit an egg to drop through the same. This aperture is closed by means of a shutter 49 having a disk 50, a little larger in diameter than the aperture 48 formed in each bottom 45. This disk has a hinge portion 52 suspended on a journal 53 in the hinge leaf 54 which is secured as at 55 on the underside of each bottom 45. The free end of the arm 51 carries a weight 56 adapted to close the aperture 48 by swinging the disk 50 in position under the same. This weight is so selected, that a slight pressure on the top of the disk will swing the latter out of its closed position; in this manner directly an egg is laid in one of the compartments, it will roll down the sloping sides of the bottom 45 and disappear through the aperture 48 as its weight will be sufficient to swing the disk 50 of the shutter 49 out of the way.

Each bottom 45 is lined with a padding 57 in the same manner as the drawer 30 and the top of the disk 50 also carries a padding 58.

Near the aperture 48 in the bottom of each compartment is provided a small stud

or spike 59 intended to carry a dummy egg 60, which has a suitable socket for the spike 59. In this manner the dummy egg 60 will remain in position in the bottom 45 and not roll down the inclined bottom or fall through the aperture 48.

Referring particularly to Fig. 2, a short chute 61 is provided under the aperture 48 of each of the side compartments. These chutes 61 are also made of sheet metal and supported under their respective bottoms 45 as at 62 and on the angle irons 37 as at 63. These chutes 61 are channel shaped and have an inclined bottom with its lowest point over the angle iron 37 the edge of which is cut away to the width of the chute, as is also the side wall 36 of the tray to form an entrance into the latter, see Figures 2 and 3. It will now be evident that an egg laid in one of the side nests will fall through the aperture 48 thereof swinging the shutter 49 out of the way and drop onto the bottom of the chute 61, whereupon it will roll down the same passing through the side entrance of the guide angle 37 into the upper end of the tray or drawer 30. As the bottom of the tray is also inclined inwardly, the egg will continue its course until it reaches the front wall of the tray or drawer 30. In order to prevent the breaking of the egg these chutes 61 are also padded as at 64 so that there is no chance of the eggs being broken because they always fall or roll on the soft padding provided for this purpose.

The middle compartment has no such chute 61 as its aperture 48 is situated directly above the rear end of the bottom of the tray or drawer 30.

A door opening 65 is furnished for each compartment in the front wall 12 of the cabinet and at the lower side of each opening is a downwardly swinging door 66 hinged as at 67. Each door has a handle 68 of band iron having a bottom arm 69 projecting at right angles from the door 66 when the latter is closed. This arm 69 serves as a support for the door, when the latter is open as seen to the right of Fig. 1, so that it will form a landing for the hen entering or leaving one of the compartments. A small latch 70 is provided for each door, so that the latter may be closed when so desired.

The padding used in the nests may be made of any suitable material such as oil-cloth, canvas, felt or manufactured straw, the kind used in the manufacture of straw hats. It is evident that besides this more or less permanent padding, loose straw, or excelsior may be spread in the bottom of each nest or compartment.

Instead of manufacturing the entire cabinet of sheet metal as has been described above, it is evident that other material such as wood or artificial board may be used or

that wooden or metallic material may be used in combination.

It will now be clearly understood, that the hens resting in the different compartments need not at all be disturbed, when a person investigates the tray or drawer 30, as the door 66 may remain closed and any eggs, that may have been laid, will be found in the forward end of the drawer 30 and will 10 consequently be visible through the transparent center portion 42 of the lid 39. When these eggs are to be removed, all that is needed is to pull out the drawer 30 by the handle 31 when they may easily be 15 reached by hand. Directly these eggs have been removed from the drawer, the latter should be returned into closed position in order to receive other eggs laid in the nest.

When cleaning the cabinet, the drawer 30 20 should be removed entirely and the door 66 opened and the roof 15 lifted off. The interior of the cabinet will in this manner be exposed and the underside thereof can also be reached by tilting the cabinet backwards.

This cabinet also provides a safe-guard 25 against rats, mice or other unwelcome visitors, as there is no possibility for them to enter the cabinet, when the drawer and doors are closed and the roof in position. To 30 make doubly sure, however, the ventilators 23 may be covered by wire mesh.

Some of the advantages in using this hen's nest will here be enumerated.

As the eggs are carried into the common 35 receptacle directly after being laid, they may be immediately collected, which insures the freshness of the eggs, particularly as they do not remain in the nest exposed to the heat from the body of the hens. For 40 the same reason, the eggs will be found in a clean, unsoiled condition, which avoids the washing of them before marketing. This washing is a very tedious work and often causes the breakage of some of the eggs.

This cabinet for laying hens is very economical, because all breakage caused by the hens stepping on the eggs, is avoided. From 45 actual test, it has been found that of 300 eggs laid in one of these cabinets, all were collected unbroken, not one being cracked or soiled.

To summarize, it may accordingly be stated, that this cabinet produces fresh and clean eggs and is very economical, as it prevents 50 loss from the breakage of the eggs and saves labor and time, as all cleaning and washing is unnecessary.

Having thus described the invention, what is claimed as new is:

1. A hen's nest in the form of a cabinet 55 having side walls, front and rear walls, a detachable roof and a slanting bottom with an aperture in its lowest part, a balanced shutter for said aperture, a slideable drawer beneath said aperture and protruding be-

yond said front wall, a suitable padding provided for said bottom, shutter and drawer, said front wall having a door opening, a door hinged at the underside of said opening, adapted to furnish a landing when open, and a centrally located, flat faced handle constituting a support for said door in open position. 70

2. A hen's nest in the form of a cabinet having side walls, front and rear walls, a 75 detachable roof and a bottom with an aperture, a balanced shutter for said aperture, a slideable drawer beneath said aperture, a suitable padding provided for said bottom, shutter and drawer, said front wall having a door opening, a door hinged at the underside of said opening, adapted to furnish a landing when open, a handle constituting a support for said door in open position, the length of said drawer being greater than 80 the distance between the front and rear walls of the cabinet, whereby a portion of the drawer will protrude beyond the front wall when in closed position, and a transparent lid covering said protruding portion 85 of the drawer. 90

3. A hen's nest in the form of a cabinet having side walls, front and rear walls, a detachable roof, partitions connecting the front and rear walls of the cabinet dividing 95 the same into a plurality of compartments, a bottom for each compartment in the shape of an inverted pyramidal frustum provided with a central aperture, a balanced shutter for each aperture and a slideable drawer beneath said compartments and chutes leading from said apertures to said drawer. 100

4. A hen's nest in the form of a cabinet having side walls, front and rear walls, a detachable roof, partitions connecting the front and rear walls of the cabinet dividing 105 the same into a plurality of compartments, a bottom for each compartment in the shape of an inverted pyramidal frustum provided with a central aperture, a balanced shutter for each aperture and a slideable drawer beneath said compartments, chutes leading from said apertures to said drawer, the length of said drawer being greater than 110 the distance between said front and rear walls of the cabinet, a transparent lid hinged to said front wall and adapted to cover the exposed portion of the drawer. 115

5. A hen's nest in the form of a cabinet having side walls, front and rear walls, a 120 detachable roof, partitions connecting the front and rear walls of the cabinet dividing the same into a plurality of compartments, a bottom for each compartment in the shape of an inverted pyramidal frustum provided with a central aperture, a balanced shutter for each aperture, a slideable drawer beneath said compartments, chutes leading from said apertures to said drawer, the length of said drawer being greater than the dis- 125 130

tance between said front and rear walls of the cabinet, a transparent lid hinged to said front wall and adapted to cover the exposed portion of the drawer, and guiding members for said drawer secured in the lower portion of the cabinet, and provided with entrances registering with said chutes.

6. A hen's nest in the form of a cabinet having side walls, front and rear walls, a detachable roof, partitions connecting the front and rear walls of the cabinet dividing the same into a plurality of compartments, a bottom for each compartment in the shape of an inverted pyramidal frustum provided with a central aperture, a balanced shutter for each aperture, a slideable drawer beneath said compartments, chutes leading from said apertures to said drawer, the length of said drawer being greater than the distance between said front and rear walls of the cabinet, a transparent lid hinged to said front wall and adapted to cover the exposed portion of the drawer, guiding members for said drawer secured in the lower portion of the cabinet, and the top part of said walls of the cabinet being provided with a rabbet furnishing a seat for said roof.

7. A hen's nest in the form of a cabinet having side walls, front and rear walls, a detachable roof, partitions connecting the front and rear walls of the cabinet dividing the same into a plurality of compartments, a bottom for each compartment in the shape of an inverted pyramidal frustum provided with a central aperture, a balanced shutter for each aperture, a slideable drawer beneath said compartments, chutes leading from said apertures to said drawer, the length of said drawer being greater than the distance between said front and rear walls of the cabinet, a transparent lid hinged to said front wall and adapted to cover the exposed portion of the drawer, guiding members for said drawer secured in the lower portion of the cabinet and provided with entrances registering with said chutes, the top part of said walls of the cabinet being provided with a rabbet furnishing a seat for said roof, and ventilators being furnished in said roof.

In testimony whereof I affix my signature.

HERMAN A. WAHLBORG. [L.S.]
